UNITED STATES PATENT OFFICE

FRITZ R. JOHNSON, OF PROVIDENCE, RHODE ISLAND

VANITY CASE

Application filed September 19, 1927. Serial No. 220,377.

In the development of the vanity case as an article of personal adornment as well as a convenient toilet accessory, and particularly in the development of the so-called "watch case" 5 or thin-edge type of vanity case, the hinge as the important service element of the vanity case, has been the subject of much experimentation, and various expedients have been devised in the effort to provide a form of 10 hinge and hinge mounting which would possess sufficient strength to withstand the strain of repeated opening and closing without however sacrificing anything of compactness and attractiveness. That is to say, the 15 problem has been to provide a sturdy hinge mounting which, however, would not require a corresponding sturdiness of case construction and hence result in a vanity case, which on account of its size, could not be conveniently 20 carried in the pocket or handbag or on account of its appearance would not possess that daintiness necessary to its use as an article of personal adornment.

To the end, therefore, of providing a commercially practicable vanity case which will solve the foregoing problem, I have devised my present invention. According to it, the casing forming members are of the usual concavo-convex type, but instead of attempting 30 to hingedly connect these members directly to each other, as is now usually done, I form the hinge connection not only as a distinct and separate connection but one which carries out the watch case type effect, and in fact 35 constitutes the knife like edge or bead of the case. Functionally, therefore, my novel hinge connection is at once both a hinge and a knife-edge beading for the case. Structurally, it takes the form of a channeled ring which 40 is so shaped as to permit it to be rolled over upon the bottom forming member of the case and to present at once both a sharply-defined relatively thin edge or bearing extending 45 about the periphery of said bottom member and a mounting for one part of the hinge element, permitting such part to be assembled on said bottom member without the necessity of soldering or otherwise fastening it directly to the bottom member itself. In 50 other words, the hinge mounting ring car-

ries one of the hinge parts and is itself rolled over the periphery of the bottom member of the case. This provides a strong and serviceable hinge connection which is practically free of all liability of becoming sprung, and admits of better gauge stock being used in the construction of the casing forming members themselves, thus resulting in a sturdier case. 55

In addition to these advantages, my case 60 also involves certain features of merit in respect to the manufacture and assembly thereof and to the ornamental aspects, as will appear more fully hereinafter. As illustrative of the principles involved, I shall describe 65 and show in the accompanying specification and drawings a form of case which I have found satisfactory in actual use and well adapted to the requirements of manufacture. This showing, however, is illustrative rather 70 than limiting, as I recognize that various modifications in the actual structure illustrated are possible and may be desirable according to circumstances. 75

In these drawings:

Fig. 1 is a top view of a vanity case in accordance with my invention, showing the case closed.

Fig. 2 is an edge view of such closed case.

Fig. 3 is a fragmentary detail view of the hinge mounting ring removed from the bottom-forming member of the case. 80

Fig. 4 is a detail view of the hinge itself, removed.

Fig. 5 is an enlarged section through the 85 case.

Fig. 6 is a detail view of the case ornament, shown in Fig. 1, removed.

Fig. 7 is an edge view of the case, partly 90 opened, to expose the interior thereof and

Fig. 8 is an enlarged detail section through the rim of the case when closed.

The case comprises a cover member 1 and a bottom member 2. These members, when shaped to form, are concavo-convex in section and may be made of sheet stock. The cover member is of less diameter than the bottom member and swings down thereover and has a snap fit at its edge therewith. This member is provided with a substantially vertically dis- 95

posed annular rim or flange 3 and with a horizontally extending finger nail operating portion 4.

The two members are hingedly connected to each other by a special form of hinge and hinge mounting. As here shown, such connection comprises a channeled hinge ring (detailed in Fig. 3) which is shaped to permit it to be rolled over the edge of the bottom member 2, said edge being slightly shouldered as indicated at 5 (Fig. 8) to receive the downward outer edge 6 of said ring.

Prior to assembly on the bottom member 2, the hinge ring, in section, presents an inner 15 substantially vertically disposed wall 7 annularly shouldered as at 8 and connected by the substantially horizontally disposed wall or web 9 with the downturned outer edge 6, (see Fig. 8) the portions 6 and 9 at their 20 juncture presenting the knife edge 10.

When rolled over the edge of the bottom-forming member 2 of the case, however, the hinge ring is slightly deformed, in that the wall 7 is forced into an upwardly and inwardly inclining position and the wall 9 into a downwardly and outwardly inclining position. These oppositely sloping walls 7 and 9 may therefore be said to form with the underlying included peripheral portion of the bottom 25 member 2 a triangle having for its base the included portion of the member 2 and for its sides the walls 7 and 9, the lower edge of the portion 7 being forced against the inner face of the included portion of the bottom 30 member 2 and the lower edge of the portion 6 being forced into the groove 5 at the outer side of the bottom member 3. This disposes the inner wall 7 of the ring in proper position to frictionally receive the depending annular 35 flange 3 of the cover member when said cover member is swung over upon the bottom member, the portions 3 and 7 having a snap fit against one another effective to hold them closed against anything but an intentional 40 separating pressure. If desired, this interlocking engagement may be augmented by providing the portion 3 with slight recesses 3' and the portion 7 with slight protuberances 7', or vice versa, adapted to interengage with 45 each other when the case is closed (see Fig. 8).

The sharply defined outer edge of the hinge ring therefore constitutes both a thin or watch-case type edge 10 and a strengthening 55 and reinforcing beading for the rim of the bottom member. The web or connecting portion 9 of the ring is utilized as the mounting or anchoring portion for one of the parts of the two-part hinge, here shown as the leaf 60 11. This leaf is inserted through a vertical slot 12 (Fig. 3) in said web 9, and is anchored thereto by means of the upturned flange 13. The other leaf of the hinge is indicated at 65 14 and is anchored over the adjacent edge portion of the cover member, as by means of the

flanges 15 which are inserted through suitable slots formed in the cover member and clinched therein, as appears in Fig. 1. Both leaves are formed with the usual rolled pintle sockets to receive the pintle 16.

By this construction of hinge and hinge mounting, I not only obtain a strong and reliable hinge connection but the hinge ring itself constitutes a relatively thin beading for the edge of the bottom member 2 in addition to its function as the independent hinge carrying member of the case.

The bottom member may carry the usual retainer for powder or rouge compact, and the cover member may carry the usual mirror 80 17, with appropriate backings as at 18 and 19 and retaining bezel 20.

One or both of the casing members may be ornamenteally embellished in any suitable manner, as by the ornament 21 which is here shown as applied to the outer face of the cover 1. This ornament may be of any shape, size or color, and as here shown is a simple stamping of conventional heart design colored in contrast to the material of the case 90 proper. It is applied to the case as a separate and independent piece, the cover being slightly depressed as shown at 22 (Fig. 5) to receive it and to allow it to lie substantially flush therewith. Preferably the cover is pierced adjacent said depression by one or more slots adapted to receive depending tongues or prongs 23 formed on the inner side of the ornament and which prongs, when inserted through said slots and clinched over on the inner face of the cover member, serve to fasten the ornamental piece on the cover.

Various modifications in the construction of my invention may obviously be resorted to if within the limits of the appended claim.

What I therefore claim and desire to secure by Letters Patent is:

A hinged container comprising concavo-convex top and bottom casing members proportioned to overlie one another when the container is closed, a single annular hinge ring affixed to said bottom member and presenting an inner wall against which the edge of the top member is adapted to abut when the container is closed, said wall extending outwardly of the container as a downwardly and outwardly inclined portion following the general curvature of the top member and substantially co-planar therewith and terminating at the edge of the bottom member in a sharply bent downwardly and rearwardly inclined attaching portion overlapping said bottom member, and a hinge disposed interiorly of said container and anchored to said ring and to said top member respectively.

F. R. JOHNSON.
